UNITED STATES PATENT OFFICE.

JOHN H. MORRISON, OF NEW YORK, N. Y.

CLEAN-OUT FERRULE.

1,208,618.

Specification of Letters Patent. Patented Dec. 12, 1916.

Application filed March 28, 1916. Serial No. 87,343.

To all whom it may concern:

Be it known that I, JOHN H. MORRISON, a citizen of the United States, residing at New York, in the county of Bronx and State 5 of New York, have invented new and useful Improvements in Clean-Out Ferrules, of which the following is a specification.

This invention relates to clean out ferrules adapted to be used in plumbing systems and it consists in the novel features 10 hereinafter described and claimed.

An object of the invention is to provide a ferrule of the character stated which includes a plug of special design which may 15 be easily and readily removed from the ferrule when desired and which may also be readily replaced therein notwithstanding the fact that the ferrule may be located at a point in the plumbing system where space 20 is limited.

With the above object in view the device includes a ferrule adapted to be applied to the drain or waste pipe of a plumbing system, the said ferrule being provided at its 25 inner sides with a screw thread located at the intermediate portion of the said ferrule. A dome shaped plug is externally threaded at its larger end and the said threads are adapted to loosely engage the 30 threads of the ferrule. A packing of oakum or similar fibrous material may be inserted between the plug and the inner surface of the ferrule above the threads and a circular wire with an upstanding end is positioned 35 upon the said oakum. Molten lead is then poured into the space between the plug and the ferrule above the wire whereby the wire is embedded in the same but the said wire 40 may be removed carrying the lead with it by applying a tool to its upstanding end after the plug has been moved in a downward direction in the ferrule.

In the accompanying drawing:—The figure is a transverse sectional view of the clean 45 out ferrule.

The structure includes a ferrule 1 adapted to be applied to the side of a drain or waste pipe of a plumbing system at the trap thereof or at any other suitable point. The said 50 ferrule 1 is provided at its interior and between its ends with a screw thread 2, there being provided a shoulder 3 at the upper end of the said thread. The ferrule 1 is preferably made of cast iron although it 55 may be formed from other suitable material. A conical dome shaped plug 4 is pro-

vided at its larger end with a thread 5 which loosely engages the thread 2 in the ferrule 1 whereby the said plug 4 may be readily screwed into engagement with the ferrule 60 by the use of the hand only. The plug 4 is provided at its exterior and at the upper end of the thread 5 with an outstanding shoulder 6 which may assume approximately the same level as the shoulder 3 when the 65 plug 4 is in engagement with the ferrule 1. The exterior conical surface 7 of the plug 4 is spaced from the inner surface of the upper portion of the ferrule 1 when the said plug is in engagement with the ferrule as 70 shown in the figure of the drawing. The plug 4 is provided at its upper end with a squared or any other polygonal projection 8. The said projection 8 is provided with an opening 9 which passes transversely through 75 the same.

When the plug 4 is in engagement with the ferrule 1, oakum 10 or any other suitable fibrous packing material is interposed between the conical surface 7 and the inner 80 surface of the ferrule 1 and above the shoulders 3 and 6 as shown in the drawing. A circular wire 11 is then laid upon the said oakum 10 and the wire is provided with an upstanding end 12 which projects beyond the 85 upper end of the ferrule 1 and which is provided at its upper extremity with an eye 13. Molten lead 14 is then poured into the upper portion of the space between the conical surface 7 of the plug 4 and the inner 90 surface of the ferrule 1 whereby the said wire 11 is embedded in the said lead. Thus the joint between the threads of the plug 4 and the ferrule 1 is effectually closed and sealed and the escape of gas or moisture at 95 the clean out ferrule is avoided.

When it is desired to remove the plug 4 from the ferrule 1 the said plug 4 is tapped from its sides a sufficient number of times to cause the filling to become loose, then, 100 a bar is passed through the opening 9 in the projection 8 and by tapping the same at the opposite end thereof the plug 4 is screwed in a downward direction in the ferrule 1 whereby the conical surface 7 of the 105 said plug disengages the inner side of the lead filling 14. By applying a suitable tool to the upper end of the eye 13 of the wire 11 the ring of lead 14 may be removed from the ferrule 1 and then the oakum 10 110 may be removed from between the lower portion of the conical surface 7 and the

inner surface of the ferrule 1. After this has been done the plug 4 is free and may be readily unscrewed from the thread 2 by using the hand inasmuch as the threads 2 and 5 loosely engage each other.

After the plug 4 has been removed from the ferrule 1 and the pipe section has been cleaned the plug 4 may be reinserted in the ferrule 1 and the thread 5 thereof may be engaged 10 with the thread 2 of the said ferrule. After this has been done oakum 10 is placed in the lower portion of the space between the conical surface 7 and the inner wall of the ferrule 1 and the ring of lead 14 which has 15 previously been removed from the said ring is reinserted in the upper portion of the space between the conical surface 7 and the inner surface of the ferrule 1 and may be secured therein by calking with the tools usually 20 employed for this purpose.

From the foregoing description taken in conjunction with the accompanying drawing it will be seen that a clean out ferrule of simple and durable structure is provided 25 and that the plug thereof may be easily and quickly removed from the ferrule and reinserted in the same. Also it will be observed that when the plug is in position in the ferrule and the oakum and metallic 30 packing are applied that the joint between the plug and the ferrule is effectually closed and will prevent the escape of moisture or gas.

Having described the invention what is 35 claimed is:—

1. A ferrule having an interiorly located thread between its ends, a cone shaped plug having a thread adapted to engage the thread of the ferrule, the conical exterior 40 surface of the plug being spaced from the inner surface of the ferrule as applied and a packing interposed between the conical exterior surface of the plug and the inner surface of the ferrule.

2. A ferrule having an interiorly located 45 thread positioned between its ends, a cone shaped plug having an exterior thread adapted to engage the thread in the ferrule, fibrous packing interposed between the exterior conical surface of the plug and 50 the inner surface of the ferrule and a metallic packing poured into the upper portion of the said space above the fibrous packing.

3. A ferrule provided with an interiorly 55 located thread positioned between the ends thereof, a conical plug having an exteriorly located thread adapted to engage the thread in the ferrule, a fibrous packing interposed between the conical exterior surface of the 60 plug and the interior surface of the ferrule, a curved wire positioned upon the said fibrous packing and having an end portion disposed above the upper end of the ferrule and a metallic packing located in the upper 65 portion of the said space between the plug and the ferrule and in which the said wire is embedded.

4. A ferrule having an interiorly located 70 thread positioned between the ends thereof, a conical plug having an exteriorly located thread which loosely engages the thread in the ferrule, a fibrous packing interposed between the exterior conical surface of the 75 plug and the interior surface of the ferrule and positioned above the upper ends of the said threads, a curved wire resting upon the fibrous packing and having an end portion which extends above the end of the ferrule, and a metallic packing fitting snugly in 80 the upper portion of the said space and in which the said wire is embedded.

In testimony whereof I affix my signature in presence of two witnesses.

JOHN H. MORRISON.
